UNITED STATES PATENT OFFICE.

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE.

TYPEWRITING MACHINE.

Application filed June 21, 1924. Serial No. 721,398.

This invention relates to typewriting machines, and is directed more particularly to line-space mechanism, line-space adjusting mechanism and platen-detent-release mechanism.

The invention includes features of construction such as enable the parts to be stamped from sheet-metal, to provide for a light-weight construction, combined with simplicity, compactness and durability, and which features are especially suitable for typewriting machines of the portable type.

Other features of the invention include an upright line-space-lever at the front of the carriage and operable by a sweeping movement of the hand in a carriage-return direction; a line-space-pawl movable rearwardly across the top of the ratchet-wheel to rotate the platen forwardly by a pulling movement; a line-space-pawl having a fixed initial stop and movable from the fixed stop to an adjustable stop for a single line-spacing unit of movement with means to shift the adjustable stop to increase the throw of the pawl from the fixed stop, for multiples of a line-space unit; a means to convey motion from a line-space-lever to a line-spacing mechanism through a plane at right angles to the movable plane of said lever by a single link having positive pivotal connections to both; a spring having a direct connection to the pawl and operative to restore the whole line-spacing mechanism to normal positions; a means forming a part of the adjustable stop to interlock with a part of the pawl, to prevent independent rotation of the platen at the end of a line-spacing movement; and a condensed arrangement of the line-spacing mechanism for a portable machine to be enclosed within a carrying case with none of the operative parts thereof projecting above the outline of the carriage-ends.

Other features and advantages will hereinafter appear.

45 In the accompanying drawings,

Figure 1 illustrates a top plan view of a platen for a portable typewriting machine, together with the line-spacing mechanisms constructed and arranged in accordance with the present invention.

Figure 2 illustrates, in front elevation, a fragmentary left-hand portion of Figure 1.

Figure 3 illustrates an elevation of Figure 2, as viewed from the left-hand end thereof.

Figure 4 illustrates an end elevation of a line-space wheel, together with line-space mechanism and line-space adjusting mechanism constructed and arranged in accordance with the present invention.

Figure 5 illustrates a fragmentary portion of Figure 2, as viewed from the rear, the typewriter end frame being shown sectioned.

Figure 6 illustrates the platen-detent-release mechanism in an actuated position to release the line-space ratchet-wheel.

Figure 7 illustrates the line-space adjusting mechanism, certain other parts with which it co-operates being shown in section.

Figure 8 illustrates a front elevational view of the line-space adjusting mechanism, together with a fragmentary portion of the platen-frame, in section.

An axle 1, to carry a revoluble platen 2, is journaled in a platen end frame 3, and provided with a finger-wheel 4 to effect rotation of the platen.

The line-space mechanism includes a line-space lever 5, having a laterally-projecting finger-piece 5', and may be in the form of a bell-crank conveniently positioned in an up-standing or vertical plane to facilitate actuation thereof by a sweeping movement of the hand in a carriage-return direction. The lever 5 is pivotally supported on a horizontally-disposed shouldered screw 6 threaded into an ear 7 which forms an integral part of the left-hand end frame 3. The line-space lever 5 is rocked in a direction indicated by the arrow in Figure 2, to effect a rearward movement of a line-space pawl in a plane at right angles to the plane of movement of the line-space-lever 5, through the intermediary of a lever 9 of the first order and a link 10. The link 10 is substantially L shaped, with its short arm fulcrumed at 11 on the short arm of the bell-crank lever 5, and its long arm having an ear 12 bent at right angles to fulcrum at 13 on the short arm of the lever 9.

The lever 9 takes a fulcrum upon the platen-axle 1, and the line-space pawl 8 is fulcrumed at 14, to the free end thereof. The line-space pawl 8 may be provided with a tooth 15 to co-operate with a line-space

ratchet-wheel 16, secured to the end of the platen 2, to effect line-space movements of the platen when the line-space lever 5 is actuated. A relatively long-range rocking movement 5 of the line-space lever 5 imparts a substantially straight-line or vertical movement to the link 10, which movement rocks the lever 9 and the pawl 8. A return-spring 17 for the whole line-spacing mechanism is connected at one of its ends to a stud 18 on the left-hand end frame 3, its other end being secured to a stud or pin 19 which projects laterally from an ear 20, that forms a part of a strip 21 brazed or otherwise suitably 10 secured to the outer face of the pawl 8, said ear depending from the pawl and over the face of the ratchet-wheel 16, to position the stud 19 to be housed within the carriage-end 3. A stud 52 is fixed on the left-hand end frame 3 15 at a point to promote a camming action by co-acting with the pin 19, and in this manner the pawl 8, just prior to reaching its limit of return movement, is raised out of co-operative relation with the ratchet-wheel by being 20 rocked on its pivot 14, so that the tooth 15 thereof just clears the teeth of the line-space ratchet-wheel, as illustrated in Figure 4. The left-hand end frame 3 is provided with an ear 22, engaged by the line-space lever 5 25 to limit the return movement thereof, by the spring 17.

The line-space movement of the line-space lever 5 may be adjusted to effect multiples of a single line-space unit of movement for the platen by means of the line-space adjusting mechanism, which, as a unit, is designated 23, see Figure 7. This mechanism includes three members designated 24, 25, and 29, all of which may be stamped from sheet-metal and 30 united to form a substantially V-shaped unit. These members taken separately include a stop-arm 24 provided with a hooked end 26, and a hub portion 27. The member 25 is made of spring steel, and is provided with a hub portion 28, to be united with the hub 27 by means of rivets. A metal strip 29 is rigidly secured to the upper end of the member 25 by means of a finger-button 30, the shank portion 31 of which protrudes through a slot 32 in the end frame 3 and unites the member 25 to the strip 29. The strip 29 is provided with a pin 33 to engage within one of a series of holes 34 in the end frame 3, to retain the hooked arm 24 in its adjusted positions. The line-space adjusting mechanism just described as a unit, is pivotally supported on the platen-axle 1, and may be set to various positions to limit the line-space movement of the pawl 8. By pressing inwardly on the finger-button 30 until a collar 35 strikes the face of the frame 3, the member 25 yields in a manner to disengage the pin 33 from whichever hole 34 it may be engaged with, then the unit 23 is rocked on its pivot until the pin 33

is in alignment with the desired hole 34, and then, by releasing the finger-button, the spring steel member 25 becomes self-restoring to move the pin 33 into engagement with the desired hole and thereby lock and maintain the line-space adjusting mechanism in adjusted position.

The line-space lever 5 may now be actuated to effect a line-space movement, the initial rearward movement of the line-space pawl 8 causing the pin 19 on the line-space pawl to ride off of the stud 22, and by the action of the spring 27 the tooth 15 engages a tooth in the line-space wheel 16.

Further actuation of the line-space pawl 8 will effect a single or double line-space movement of the platen, according to the adjustment of the stop-arm 24 and which arm arrests the movement of said line-space pawl by engaging the pin 19, as illustrated in dot-and-dash lines in Figure 4. Thus by varying the position of the stop-arm 24 relatively to the pin 19, by the plugging-in action of the finger-button 30, the range of movement of the line-space pawl 8 is predetermined for either a single or a double line-spacing distance. Of course it will be understood that a third hole 34 may be provided, so that the herein-described line-space adjusting mechanism may be adjusted to effect a triple line-spacing movement, if desired.

The platen-detent-release mechanism includes a detent-lever designated 36, stamped from sheet-metal, and formed into a bell-crank with arms 37 and 38, offset from each other and connected substantially at the pivotal point, by a web 39 which is substantially U-shaped, as viewed from the rear in Figure 5. The lever is pivotally supported by a screw 40, with the upstanding arm 38 aligned with the inner wall of the end frame, and with the arm 37 carrying at its lower end a detent or roll 41 to co-operate with the teeth of the line-space wheel 16. A coil-spring 42, having its ends connected to a roll-supporting stud 43 and to a stud 44 secured to the end frame 3, acts to urge the detent or roll 41 into engagement with the line-space wheel, as indicated in Figure 3. A detent-release lever designated 45 is pivotally supported for rocking movement on a shouldered stud 46. A stud 47, carried at the upper end of the lever 45, protrudes through a slot 48 in the end frame 3, and is provided with a finger-knob 49. At the pivotal support for said lever, a slot 53 is provided, open at one end to facilitate placement of the lever 45 on its supporting stud 46. To move the detent-release lever 45 to a position to withdraw the roll 41 to an ineffective position, as illustrated in Figure 6, a cam-face 50 is provided on the lever 45, which, when rocked in a clockwise direction from its normal inoperative position, as indicated in dotted lines in Figure 3,

to an actuated position, as illustrated in Figure 6, causes the cam to co-act with the arm 38, to rock the detent-lever 36 and disengage the roll 41 from the ratchet-wheel to permit the 5 platen to be revolved freely in either direction by the finger-wheel 4. It will be particularly noted that the high part of the cam face 50, when in the detent-releasing position of Figure 6, is in a horizontal plane cutting the axis 10 of the detent-release lever 46, which corresponds to a dead-center position with respect to the axis of said detent-release lever. Hence an interlock is formed between the two levers to retain them in the 15 actuated position against the action of the spring 42, and such co-action between the two levers prevents accidental replacement of the detent-roll 41. When the detent-release lever is moved slightly to break 20 the dead-center or interlocking position, the action of the spring 42, in restoring the detent-roll 41, converts the rounded end of the arm 38 into a cam to restore said detent-release lever to normal or inoperative position, 25 the slot 48 in the platen-frame co-acting with the shank portion of the finger-knob 49, to limit movement of said lever to both normal and actuated positions. The inertia of the heavy platen tends to overthrow its line- 30 spaced position at the end of a line-spacing operation, and, while the spring-detent-roll will act to justify the position of the platen, it is an advantage to positively lock some operating part, to prevent an independent 35 movement of the platen. As already described, the stop-arm 24 has formed thereon a hook 26, and when the line-space pawl 8 is shifted to the dot-and-dash position of Figure 4, the stud 19 is arrested 40 by the arm 24, and said stud has also passed under the hook 26, and any tendency of a tooth of the ratchet-wheel 16 to cam by the tooth 15 of the pawl will be checked by said hook holding the tooth 15 locked between adjoining teeth of the ratchet-wheel, and will 45 effectively prevent an independent rotation of the platen in either direction at the end of a line-spacing movement.

It will be noted that when the line-spacing parts are at their normal positions, as at Figure 4, the axis 14 of the pawl 8 and the two studs 19 and 18 practically intersect a straight line drawn through them, and the action of the spring 17 upon the pawl 8 holds the pawl 50 in a state of equipoise. Hence, the same spring that has sufficient power to restore the whole line-spacing mechanism to normal exerts only a comparatively light spring-tension between the two studs 19 and 52 during their 55 camming action in raising the pawl 8.

Variations may be resorted to within the scope of the invention, and portions of the improvements may be used without others.

Having thus described my invention, I 60 claim:

1. In a typewriting machine having a platen and a platen-axle, the combination with a line-spacing mechanism to drive the platen, including a toothed ratchet-wheel, a line-space pawl, and a line-space lever, of a 70 lever of the first order fulcrumed upon the platen-axle, one arm thereof connected to the line-space pawl and the other arm thereof connected to be operated by the line-space lever forwardly of the platen-axle. 75

2. In a typewriting machine, the combination with a revolute platen having an axle, of a line-space ratchet-wheel to drive the platen, a line-space pawl, a lever having an arm extending rearwardly of the platen-axle 80 and connected to the pawl, said lever being pivotally supported on said platen-axle, a line-space finger-lever operatively connected forwardly of the platen-axle to the other arm of said first-named lever to effect line-space 85 movement of the ratchet-wheel, and a stop to arrest the line-space movement of said finger-lever, the range of movement of said finger-lever being varied in accordance with the adjustment of said stop to predetermine a 90 line-space movement for the platen.

3. In a typewriting machine, the combination with a revolute platen having an axle, of a line-space ratchet-wheel, a line-space pawl, a lever connected to said pawl, a line-space bell-crank lever having a finger-piece and being pivotally supported in an upstanding or vertical plane on a horizontal pivot below the axis of said platen axle, a link connecting said levers whereby actuation of said bell-crank lever effects line-space movement of said ratchet-wheel, and a stop mounted upon the platen-axle to arrest the first-named lever, to determine a line-spacing swing for the bell-crank lever. 100 105 110

4. In a typewriting machine, the combination with a revolute platen having an axle and mounted in a platen-frame, of a line-space ratchet-wheel, a line-space pawl to co-operate with said wheel, and means to actuate said pawl to effect line-space movement of said ratchet-wheel, including a lever of the first order pivotally supported on the axle of said platen to connect at one end to said pawl, a line-space bell-crank lever supported at the front of the platen upon a pivot in a plane below and at right angles to the axis of said platen, and a link connecting said bell-crank lever to the opposite end of said lever of the first order, whereby the direction of movement of said link will be reversed for the line-space pawl, said line-space lever having a finger-piece extending from said pivot to a point substantially flush with the top of the platen-frame. 115 120 125

5. In a typewriting machine, the combination with a revolute platen and a carriage-frame end, of a line-space ratchet-wheel, a line-space pawl having an ear depending therefrom to overhang the face of the ratchet- 130

wheel, a stud projecting laterally from said ear to be housed within the carriage-end, and means fixed within the carriage-end to coact with said stud to cam the pawl out of co-operative relation with said ratchet-wheel when said pawl moves to its return position.

6. In a typewriting machine, the combination with a revoluble platen and a carriage-frame end, of a line-space ratchet-wheel, a pivoted line-space pawl having a tooth to engage the ratchet-wheel and an ear depending therefrom over the side of the ratchet-wheel, a pawl-stud projecting laterally from said ear below the position of the tooth to be housed within the carriage-end, a stud within the carriage-end coacting with said pawl-stud to cam the pawl out of co-operative relation with said ratchet-wheel when said pawl returns to normal position, and a spring secured to the pawl to jointly restore said pawl and oppose the camming of the pawl over the stud, the spring-anchors and pawl-pivot being substantially in a straight line when said pawl is in normal position to reduce the spring-tension necessary to effect camming of the pawl.

7. In a typewriting machine, the combination with a revoluble platen, of an end frame therefor, a line-space ratchet-wheel, a line-space pawl comprising a tooth to cooperate with the ratchet-wheel and having a depending ear, said tooth co-operating with the ratchet-wheel to effect line-space movement thereof, a pin projecting laterally from said ear, below said tooth and in vertical alignment therewith, a stud secured to said end frame, to co-operate with said pin to cam said tooth from operative engagement with said ratchet-wheel when said pawl is moved to return position, an additional stud secured to said end frame, and a spring connecting said pin with the latter named stud to effect movement of said pawl to return position.

8. In a typewriting machine, the combination with a revoluble platen, of a line-space ratchet-wheel, a line-space pawl, plural members co-operating to cam the pawl out of co-operative relation with the ratchet-wheel when the pawl is returned to normal position, a stop adjustable circumferentially of said wheel and co-acting with one of said members to limit the range of movement of said pawl, and means forming a part of said stop, to lock the pawl in engagement with the ratchet-wheel at the end of a line-space movement of the platen.

9. In a typewriting machine, the combination with a revoluble platen, of a line-space ratchet-wheel, a line-space pawl to engage said ratchet-wheel, camming members, one of which is movable with said pawl, to cam said pawl out of engagement with said ratchet-wheel when the pawl is moved to return position, a stop adjustable circumferentially of said wheel and settable to one pawl-

camming member to limit the range of movement of the pawl and thereby determine a line-space movement for said platen, and means settable with the stop and operative at the end of a line-space movement to prevent displacement of the pawl from the ratchet-wheel by interlocking with the last-named camming member.

10. In a typewriting machine, the combination with a revoluble platen, of a line-space ratchet-wheel, a line-space pawl comprising a tooth and a laterally projecting pin, means to cooperate with said pin to cam said pawl out of co-operative relation with said ratchet-wheel when moved to return position, and means adjustable to vary the range of the forward movement of said pawl, including a stop-arm having a hooked end to both intercept and lock the pin, to prevent the displacement of the pawl by the ratchet-wheel.

11. In a typewriting machine, the combination with a platen revoluble upon a platen-axle, of a line-space ratchet-wheel, a line-space pawl having a tooth to engage said ratchet-wheel, a pin projecting laterally from said pawl, and a stop-arm pivotally mounted upon the platen-axle to intercept the movement of said pin to stop said pawl at the end of a line-spacing movement, said stop-arm having means to interlock with said pin to prevent displacement of the pawl by the inertia of the platen.

12. In a typewriting machine, the combination with a revoluble platen having an axle, of a line-space ratchet-wheel, a line-space pawl having a tooth to engage said ratchet-wheel, a pin projecting laterally from said pawl, a stop-arm pivotally mounted upon the platen-axle to intercept and lock said pin to stop said pawl at the end of a line-spacing movement, and means to adjust said stop-arm to vary the range of movement of said pawl to predetermine the extent of movement for said platen.

13. In a typewriting machine, the combination with a platen revoluble upon a platen-axle, of a line-space ratchet-wheel, a line-space pawl engaging said ratchet-wheel and effecting line-space movement thereof, and means controlling the line-space movement of said pawl by varying its range of movement, said means including a stop-arm and a spring-pressed locking arm, both arms pivotally mounted upon the platen-axle, said spring-arm being operative to lock the stop-arm at predetermined stop positions.

14. A mechanism adjustable to control the line-space movement of a line-space pawl, by varying its entire range of movement in accordance with the desired number of line-space movements of the platen, including a stop-arm and a stop-adjusting arm rigidly connected together and pivotally supported upon the axle of a typewriting machine, said adjustable arm yielding laterally under pres-

sure to unlock said arm to permit adjustment of the stop-arm, and being self-acting to effect a plugging-in operation to lock said stop-arm in adjusted position.

- 5 15. A mechanism adjustable to control the line-space movement of a line-space pawl by varying its entire range of movement in accordance with the desired number of line-space movements of the platen, comprising, 10 in combination, three members united to form substantially a **V**, one of said members consisting of a hooked stop-arm having a hub by means of which the **V** is pivotally supported on the platen-axle of a typewriting 15 machine, the second member consisting of a strip of spring steel having a hub at which point said strip and stop-arm are united, and a finger-button having a shank, and the third member consisting of a strip united to said 20 second-named strip by said shank and having a locking pin projecting laterally therefrom.
16. In a typewriting machine, the combination with a revoluble platen having an axle, of an end frame for said platen, a line-space 25 ratchet-wheel, a line-space pawl to engage said ratchet-wheel to effect line-space movement thereof, and mechanism adjustable to control the line-space movement of said line-space pawl, by varying its entire range of 30 movement in accordance with the number of line-space movements of the platen, comprising a stop-arm pivotally supported on said platen axle, to limit movement of said pawl, a laterally yielding arm connected to said 35 stop-arm and having a finger-button secured thereto, a slot in said end frame engageable by the shank of said button, a strip united to said yielding arm by said shank and hav-

ing a pin projecting laterally therefrom, and apertures in said end frame engageable by 40 said pin to lock said stop-arm in adjusted position, said second-named arm yielding laterally by pressure on said finger-button to disengage said pin from an aperture to unlock said stop-arm and permit adjustment 45 thereof.

17. In a typewriting machine, the combination with a platen mounted in a carriage-frame, a line-space ratchet-wheel revoluble upon the platen-axle, and a line-space pawl 50 engageable with said wheel, of a line-space lever pivoted below the platen-axle on an axis transverse to the platen and having a finger-piece extending upward from the pivot to a point substantially flush with the top of 55 the carriage-frame, and connections between said lever and said pawl to actuate the latter upon the sweep of the lever in a carriage-return direction.

18. In a typewriting machine, the combination with a revoluble platen mounted within a carriage-frame, of a line-space ratchet-wheel secured to said platen, a pawl for actuating said wheel, a bell-crank line-space 65 lever pivoted on a horizontal axis transverse 65 to the axis of said platen and below the bottom of the platen, one arm of said lever serving as a finger-piece and extending to a point approximately on a level with the top of the carriage-frame, and connections between said pawl and the other arm of said line-space lever to impart line-space rotation to said ratchet-wheel upon movement of said finger-piece in a carriage-return direction. 70

ALFRED G. F. KUROWSKI.
